RAILWAY SIGNALING APPARATUS

Andrew J. Sorensen, Edgewood, Pa., assignor to
The Union Switch & Signal Company, Swiss-
vale, Pa., a corporation of Pennsylvania

Application August 8, 1939, Serial No. 289,006

10 Claims. (Cl. 246—34)

My invention relates to railway signaling apparatus, and particularly to apparatus of this character for supplying coded current to the rails of a track section to control either wayside 5 or cab signaling apparatus or both.

In railway signaling it has been proposed to use coded direct current of different code rates or frequencies for controlling wayside or cab signaling apparatus or both. Such impulses of 10 direct current are preferably of high peak voltage as an aid to the shunting sensitivity of the track circuit and of short duration to require only a relatively low energy output from the current source which ordinarily is a battery. The 15 coding device usually provided for such systems includes a contact member which is moved into and out of engagement with a stationary contact for closing and opening the circuit connection with the current source with the result 20 the code rate is equal to the rate such contact member is operated and high code rates place a severe operating requirement on the contact member. In other words, high code 25 rates are difficult to obtain because of the mechanical limitations of the vibrating contact member of the coding device.

Accordingly a feature of my invention is the provision of novel and improved means whereby 30 coded direct current of a predetermined code rate may be obtained by use of coding means whose contact member may be operated at only a fraction of the code rate and longer life and more reliable operation of the coding means results. Other features and advantages of my 35 invention will appear as the specification progresses.

I shall describe several forms of apparatus embodying my invention, and shall then point out the novel features thereof in claims.

40 In the accompanying drawing, Fig. 1 is a dia-
grammatic view of one form of apparatus em-
bodying my invention when used to supply code
impulses of direct current to the rails of a track
section and wherewith the code rate of the cur-
rent impulses is double the rate of operation of
45 the coding device. Fig. 2 is a diagrammatic
view of a modification of the apparatus of Fig.
1, and which also embodies my invention. Fig.
3 is a diagrammatic view of another form of
50 apparatus embodying my invention when used to
supply code impulses of direct current to the
rails of a track section and wherewith the code
rate of the impulses may be four times the rate
at which any one contact member of the coding
55 means is operated. Fig. 4 is a diagrammatic

view of a modified form of the apparatus of Fig. 3 and which also embodies of my invention.

In each of the several views like reference characters designate similar parts.

Referring to Fig. 1, the reference characters **1a** and **1b** designate the track rails of a stretch of railway track which is formed with a track section **A—B** by the usual insulated rail joints, and which track section may be one section of a series of consecutive sections of a wayside and/or **10** cab signal system.

The track section **A—B** is provided with a track circuit which includes means for supplying to the rails at the exit end of the section code impulses of direct current, and a track relay responsive to such code impulses of current connected across the rails at the entrance end of the section. Such track relay is not shown in the drawing of the present application since such track relays are well known in the art **20** and they form no part of my present invention. In case of cab signals the train is equipped with an inductor mounted on the train in advance of the leading pair of wheels and in inductive relation with the track rails in the well-**25** known manner.

The means for supplying such code impulses of direct current consists of a reactance device or transformer **TF**, a battery **5** and a coding device indicated as a whole by the reference character **CD**. As here shown the secondary winding **6** of transformer **TF** is connected across the track rails **1a** and **1b** over wires **7** and **8**, respectively. The primary winding **9** of transformer **TF** has one terminal connected with one terminal of battery **5** over wire **10** and has its other terminal connected with the other terminal of battery **5** over a contact member of coding device **CD** as will shortly be explained.

The coding device **CD** comprises a polar relay **PR**, a transformer **T1** and a condenser **11**. The secondary winding **12** of transformer **T1** is connected in series with condenser **11** across the operating winding **28** of relay **PR**. Windings **12** and **28** and condenser **11** are proportioned to provide a resonant circuit and for the purpose of illustration I shall assume this circuit has a natural period of 180 cycles per minute or 3 cycles per second. The primary winding **13** of transformer **T1** has its two outside terminals connected with normal polar contact **14** and reverse polar contact **15** of relay **PR** over wires **16** and **17**, respectively. The center terminal of primary winding **13** is connected with one terminal of a battery **18** over wire **19**, and the **50**

other terminal of battery 18 is connected with a contact member 21 of relay PR over wire 20, contact member 21 being adaptable of engaging either normal contact 14 or reverse contact 15. 5 Polar relay PR is provided with a second contact member 22 adaptable of engaging either a normal polar contact 23 or a reverse polar contact 24. Normal contact 23 and reverse contact 24 are connected together by wire 25 and 10 the two contacts in multiple are connected with the other terminal of primary winding 9 of transformer TF over wire 26, contact member 22 being connected with the other terminal of battery 5 over wire 27 to complete a circuit by which 15 direct current is supplied from battery 5 to primary winding 9. When current of one polarity which I shall term normal polarity is supplied to the operating winding 28 of polar relay PR its contact members 21 and 22 are operated to 20 their left-hand position, that is, the position illustrated by solid lines in Fig. 1, where they engage normal polar contacts 14 and 23, respectively. When current of reverse polarity is supplied to winding 28 of relay PR the contact members 21 and 22 are operated to their right-hand positions, that is, the positions illustrated by dash lines, where they engage reverse polar contacts 15 and 24, respectively.

In explaining the operation of the apparatus 30 of Fig. 1, I shall assume that relay PR has just been operated to its reverse position closing contact 21-15 so that current flows in the lower portion of primary winding 13 of transformer T1. During the building up of the current to 35 its steady value, an electromotive force is induced in secondary winding 12 of transformer T1 of a selected polarity and which electromotive force excites the resonant circuit so that the current flowing therein oscillates at the 40 natural period of the circuit. The parts are so arranged that during the first charge of condenser 11, the current flowing in the resonant circuit is of the direction that energizes relay PR at reverse polarity so that contact members 21 and 22 of relay PR are held at the 45 reverse or right-hand position.

When condenser 11 next discharges due to the 50 free oscillations set up in the resonant circuit, the current flows in the circuit in the opposite direction to that flowing in the circuit when condenser 11 was charged so that relay PR now becomes energized at normal polarity and its 55 contact members 21 and 22 are operated to their normal or left-hand positions. Upon opening contact 21-15, the current decays in the lower portion of primary winding 13 and upon closing contact 21-14 current builds up to a steady value in the top portion of primary winding 13. The 60 connections are such that this dying down and building up of current in the two portions of primary winding 13 unite to induce an electromotive force in secondary winding 12 which causes current to flow in the resonant circuit that energizes relay PR at normal polarity and 65 again charges condenser 11. Since this charging current is of the same polarity as that which operated relay PR to close its normal contacts, the contact members 21 and 22 are held at the 70 normal position. When condenser 11 next discharges, however, the relay PR is energized at reverse polarity and its contact members are 75 operated back to their reverse or right-hand positions. The current flowing in the top portion of primary winding 13 now decays and the current flowing in the lower portion of primary wind-

ing 13 builds up to a steady value and it follows that an electromotive force is now induced in secondary winding 12 which causes current to flow in the resonant circuit that energizes relay PR at reverse polarity and charges condenser 11. This cycle of operation just described is then repeated over and over again, the relay PR being operated at a rate which corresponds to the natural period at which the resonant circuit is proportioned and which period I have 10 here assumed for the purpose of illustration to be 180 cycles per minute.

It is clear that either the inductance or the capacity or both of the resonant circuit including winding 28 of relay PR can be readily varied 15 according to different traffic conditions so that relay PR is operated at a different predetermined rate for each different traffic condition.

The contact member 22 is operated to alternately engage normal contact 23 and reverse contact 24 at the rate at which relay PR is operated, the period the contact member 22 engages contact 23 or contact 24 being approximately one-half of each operation cycle of the relay, and the period contact member 22 is in transit 25 and not in engagement with either contact 23 or 24 being relatively short and only a small portion of the operation cycle.

Each period contact 22-23 or 22-24 is closed 30 current builds up in the primary winding 9 of transformer TF, the current building up to approximately the steady value because of the relatively long period contact 22-23 or 22-24 is closed. When contact member 22 is in transit between its two extreme positions the circuit for 35 primary winding 9 is opened and the energy stored in the magnetic circuit of transformer TF decays. The parts are so proportioned as to the time constant of the circuit including primary winding 9 that the energy builds up relatively slowly in transformer TF and the electromotive force induced in secondary winding 6 thereby is small and can be neglected. The decay of the stored energy is relatively rapid and a relatively large electromotive force is induced 40 in secondary winding 6 and in turn applied across 45 the track rails causing a current impulse to flow in the rails. It follows that two effective code impulses of current are supplied to the rails of track section A-B each operation cycle of the 50 coding device CD, each movement of contact member 22 being effective to produce a current impulse.

Since current flows in primary winding 9 always in the same direction and the effective electromotive force induced in secondary winding 6 is caused by the decay of the stored energy, the effective current impulses supplied to the rails of section A-B are all of like polarity.

In Fig. 2, the track rails 1a and 1b are formed 55 with a track section A-B, across the rails at the exit end of which is connected secondary winding 6 of track transformer TF the same as in Fig. 1. The primary winding 9 of transformer TF of Fig. 2 is connected with battery 5 over a contact member 39 of a coding device CD1, a condenser 29 being preferably connected across the terminals of primary winding 9.

The coding device CD1 comprises a polar relay PR1 having a normal winding NW and a reverse winding RW and is provided with a contact member 30 capable of making engagement with either a normal polar contact 31 or a reverse polar contact 32. Polar relay PR1 is preferably characterized by the fact that the stroke of its polar

armature to which contact member 30 is attached will be completed if energy is applied to either winding for a long enough interval to open the polar contact in the last position. In other words, when current is supplied to winding NW or RW for an interval long enough to move contact member 30 away from its last position the contact member 30 is moved to its other extreme position without further energization of the respective winding. A relay which may be made to operate in the manner just described is covered by Letters Patent of the United States, No. 1,790,671 granted to Branko Lazich on February 3, 1931, for Electrical relays. In the instant application the polar relay PR1 is provided with two windings disposed for reversibly energizing the relay whereas in the patent the relay is shown provided with a single winding to which current is reversibly supplied, such equivalent arrangements for the windings of a polar relay being readily understood by those skilled in the art.

Assuming relay PR1 to be at its normal position, that is, the position shown in Fig. 2, current flows from one terminal of battery 5 over reverse winding RW, normal polar contact 30-31, winding 9 of transformer TF and to the other terminal of battery 5. This current gradually increases until it reaches a value sufficiently high to operate the relay, at which point the contact member 30 is moved to break engagement with normal contact 31 and to make engagement with reverse contact 32, it being understood, of course, that winding RW is so connected as to energize relay PR1 at reverse polarity. While current is building up magnetic energy is stored in transformer TF. The parts of the circuit including primary winding 9 are preferably so designed with respect to the time constant of the circuit that energy builds up rather slowly and the voltage induced in secondary winding 6 at this time is so small that it can be neglected. While contact member 30 is in transit the circuit is interrupted and the stored magnetic energy in transformer TF decays and by transformer action a relatively high electromotive force is induced in secondary winding 6 which in turn causes an impulse of current to flow in the track rails of section A-B, the condenser 29 aiding in the operation. When contact member 30 engages contact 32 current flows from battery 5 over normal winding NW, reverse polar contact 30-32, primary winding 9 and back to battery 5.

Again current gradually increases until it reaches a value sufficiently high to operate relay PR1 at which point contact member 30 is moved back to its normal position, since winding NW is connected to energize the relay at normal polarity. While the current is building up magnetic energy is again stored in transformer TF but because of the time constant of the circuit little or no voltage is induced in secondary winding 6. However, when contact member 30 is in transit back to its normal position the circuit is interrupted and a relatively high electromotive force is induced in secondary winding 6 and an effective current impulse is supplied to the track rails because of the rapid decay of the energy stored in transformer TF. The windings of relay PR1 and of transformer TF are so adjusted and proportioned that when current is sufficiently strong to operate the relay a value of the current has been reached that causes a current impulse of proper magnitude to be supplied to the track rails. The parts are further so proportioned that relay PR1 is operated at a predeter-

mined rate of say, for example, 180 cycles per minute or 3 cycles per second.

It is to be observed that two current impulses are supplied to the track rails each operation of the coding device CD1 of Fig. 2. That is to say 5 the contact member 30 of relay PR1 is effective during each movement to cause an effective current impulse to be supplied to the track rails. Since the current supplied from battery 5 to primary winding 9 always flows in the same direction in winding 9 and since the effective current impulse supplied to the track rails is always produced by the decay of the stored energy the current impulses flowing in the rails are all of the same polarity. 10 15

In Fig. 3, the secondary winding 6 of track transformer TF is connected across the rails 1a and 1b at the exit end of track section A-B the same as in Fig. 1. The primary winding 9 of transformer TF of Fig. 3 is supplied from battery 5 with current which is periodically interrupted or coded by a coding device CD2. Coding device CD2 comprises two slow acting relays R1 and R2 both of which are operated by current supplied from battery 5. Relay R1 controls over its front contact 33 the energization of relay R2, and relay R2 controls over its back contact 34 the energization of relay R1 as will be readily understood by an inspection of Fig. 3. Consequently, as long as current is supplied by battery 5, relays R1 30 and R2 are operated in a cyclic manner, the rate of operation being determined by the retardation periods of the relays. In other words, coding device CD2 divides time into successive operation cycles or periods each of which is subdivided 35 into four substantially equal intervals. To be explicit, and assuming at the start that both relays R1 and R2 are released, current first flows from the left-hand terminal of battery 5 over winding of relay R1, back contact 34 of relay R2 and to 40 the right-hand terminal of battery 5, and relay R1 is picked up at the end of its slow pick-up period to close front contact 33 which completes the first interval of the operation period or cycle. With front contact 33 closed current flows from 45 battery 5 over front contact 33, winding of relay R2 and back to battery and relay R2 is picked up at the end of its slow pick-up period to open back contact 34 completing the second interval of the operation period. With back contact 34 50 opened relay R1 is deenergized and releases at the end of its slow release period to open front contact 33 completing the third interval of the operation period. With front contact 33 opened relay R2 is deenergized and releases at the end of 55 its slow release period to close back contact 34 and thereby completes the fourth interval of the operation period. Both relays R1 and R2 are now released ready to start a second operation cycle. Obviously the above described operation cycle 60 will be completed over and over again as long as current is supplied from battery 5 to relays R1 and R2.

Relays R1 and R2 are provided with contact members 39 and 40, respectively, for controlling 65 the supply of current from battery 5 to primary winding 9 of transformer TF. Contact member 39 of relay R1 is connected with one terminal of primary winding 9 while front contact 35 and back contact 36 associated with contact member 70 39 are connected in multiple and the two are connected in series with contact member 40 of relay R2. Front contact 38 and back contact 37 associated with contact member 40 are connected in multiple and the two are connected with 75

one terminal of battery 5, the other terminal of battery 5 being connected with the other terminal of primary winding 9 to complete the circuit therefor.

5 It is clear that during the first interval of an operation cycle of coding device CD2, current is supplied from battery 5 to primary winding 9 over a circuit including contact 39-36 of relay R1 in series with contact 40-37 of relay R2, and energy is stored in transformer TF, the time constant of the circuit being such however that little or no voltage is induced in secondary winding 6 during the building up of the current. At the end of the first interval of the operation cycle 10 of coding device CD2 relay R1 is picked up to move contact member 39 from engagement with back contact 36 to engagement with front contact 35, the circuit for primary winding 9 is interrupted while contact member 39 is in transit 15 and an electromotive force is induced in secondary winding 6 due to the decay of the stored energy in transformer TF, and which electromotive force causes a first current impulse to be supplied to the rails of section A-B. During the second 20 interval of the operation cycle current again is supplied to primary winding 9 over a circuit including contact 39-35 of relay R1 in series with contact 40-37 of relay R2, and energy is again stored in transformer TF. At the end of the 25 second interval, relay R2 is picked up, the circuit for primary winding 9 is interrupted while contact member 40 is in transit between back contact 37 and front contact 38 and an electromotive force is induced in secondary winding 6 30 due to the decay of the stored energy so that a second current impulse is supplied to the track rails. During the third interval of the operation cycle energy is stored in transformer TF due to current supplied from battery 5 to primary winding 9 over a circuit including contact 39-35 of relay R1 in series with contact 40-38 of relay R2. At the end of the third interval relay R1 is released and the circuit is interrupted while contact member 39 is in transit between 35 front contact 35 and back contact 36 and a third current impulse is supplied to the track rails due to the decay of the energy stored in transformer TF. During the fourth interval of the operation cycle current flows to primary winding 9 from 40 battery 5 over contact 39-36 of relay R1 in series with contact 40-38 of relay R2 and energy is again stored in transformer TF so that at the end of the fourth interval relay R2 is released 45 interrupting the circuit so that while contact member 40 is in transit between front contact 38 and back contact 37 a fourth current impulse is supplied to the track rails.

Consequently four current impulses are supplied to the rails of section A-B each operation cycle of coding device CD2 and a relatively high code rate of current impulses can be obtained with relatively low operation rate for the coding device.

In the form of the invention disclosed in Fig. 4, the secondary winding 6 of track transformer TF is connected in series with a secondary winding 41 of a second track transformer TF1 across the rails 1a and 1b at the exit end of section A-B. In Fig. 4, the coding device CD2 comprises 60 two slow acting relays R1 and R2 the same as in Fig. 3 with the result that each operation cycle of the coding device is divided into four substantially equal intervals.

Assuming both relays R1 and R2 of Fig. 4 are 65 released, current is supplied from battery 5 to

primary winding 9 of transformer TF over contact 39-36 of relay R1 and current is supplied to primary winding 42 of transformer TF1 over contact 40-37 of relay R2, and magnetic energy is stored in both transformers TF and TF1. 5 At the end of the first interval of the operation cycle relay R1 is picked up to transfer contact member 39 from engagement with back contact 36 into engagement with front contact 35, the circuit for primary winding 9 of transformer TF 10 is interrupted and an electromotive force is induced in secondary winding 6 which causes a first current impulse to be supplied to the track rails. With contact 39-35 of relay R1 closed current again is supplied to the primary winding 9 and 15 energy is again stored in transformer TF. At the end of the second interval of the operation cycle relay R2 is picked up to transfer contact member 40 from engagement with back contact 37 20 into engagement with front contact 38, the circuit for primary winding 42 of transformer TF1 is interrupted and an electromotive force is induced in secondary winding 41 of transformer TF1 which electromotive force causes a second current impulse to be supplied to the track rails. 25 At the end of the third interval of the operation cycle relay R1 is released and the circuit for primary winding 9 is interrupted while contact member 39 is in transit between front contact 35 and back contact 36. Under these conditions, a third impulse of current is supplied to the track rails due to the decay of the energy stored in transformer TF. At the end of the fourth interval relay R2 is released and the circuit for primary winding 42 of transformer TF1 30 is interrupted while contact member 40 is in transit between front contact 38 and back contact 37 so that a fourth impulse of current is supplied to the rails due to the electromotive force induced in secondary winding 41 of transformer 40 TF1 because of the decay of the magnetic energy stored therein.

It is clear therefore that the apparatus of Fig. 4 is effective to cause four current impulses to be supplied to the track rails of section A-B 45 during each operation cycle of the associated coding device CD2, and that the impulses are transmitted alternately from transformers TF and TF1.

Although I have herein shown and described 50 only a few forms of apparatus embodying my invention, it is understood that various changes and modifications may be made therein within the scope of the appended claims without departing from the spirit and scope of my invention.

Having thus described my invention, what I claim is:

1. In combination, a section of railway track, a track transformer having a secondary winding 60 connected across the rails of said section, a source of direct current, a coding device having a contact member operable to a first and a second position for engaging a first and a second contact respectively, means for operating said device, and circuit means including said contact member in series with said first and second contacts in multiple to connect said source of direct current across the primary winding of said transformer to supply to the rails of said section an effective 65 code impulse of direct current each time said contact member is in transit between said first and second contacts.

2. In combination, a section of railway track, a track transformer having a secondary winding 70

- connected across the rails of said section, a source of direct current, a normally active coding device having a contact member periodically moved between a first and a second position for 5 periodically engaging a first and a second contact respectively, and circuit means including said contact member in series with said first and second contacts in multiple to connect said current source with a primary winding of said transformer former to supply to the rails of said section an effective code impulse of current each time said contact member is moved between its two positions. 10
3. In combination, a section of railway track, a source of direct current, a coding device having a contact member operable to a first and a second position to engage a first and a second contact respectively, means to operate said coding device at a predetermined rate, and circuit means including said contact member in series with said first and second contacts in multiple to connect said current source with the rails of said section for supplying to the rails effective code impulses of direct current at a rate equal to twice 25 said predetermined rate. 15
4. In combination, a section of railway track, a track transformer having a secondary winding connected across the rails of said section, a source of direct current, a polar relay having a first and a second contact member each of which is adaptable of engaging a normal and a reverse polar contact, means including a current source and said first contact member with its associated normal and reverse polar contacts to reversibly 30 energize said relay to cause the relay to be operated at a predetermined rate, and circuit means including said second contact member and its normal and reverse polar contacts connected in multiple to connect said source of direct current 35 across a primary winding of said transformer to supply to the rails of said section effective code impulses of direct current at a rate equal to twice said predetermined rate. 20
5. In combination, a section of railway track, a track transformer having a secondary winding connected across the rails of said section, a source of direct current, a polar relay having a first and a second contact member each capable of engaging respective normal and reverse polar contacts, another transformer having a secondary winding connected with the winding of said relay, another source of direct current, means including said first contact member with its associated normal and reverse contacts to alternately 40 connect said other source to a first and a second portion of the primary winding of said other transformer to cause said relay to be reversibly energized by the electromotive forces induced in said secondary winding to operate the 45 relay at a predetermined rate, and means including said second contact member with its associated normal and reverse contacts connected in multiple to connect said first mentioned current source with a primary winding of said track transformer to supply to the rails of said section effective code impulses of direct current at a rate equal to twice said predetermined rate. 50
6. In combination, a section of railway track, a track transformer having a secondary winding connected across the rails of said section, a source of direct current, a polar relay, another transformer having a secondary winding connected with a winding of said relay through a condenser to form a resonant circuit tuned to resonance 55 at a predetermined frequency, means including 60
- a normal and a reverse polar contact of said relay to alternately supply direct current to two portions of a primary winding of said other transformer to excite said resonant circuit by the electromotive forces induced in said secondary winding to operate said relay at a rate equal to said predetermined frequency, and means including another polar contact of said relay to connect said source of direct current with a primary winding of said track transformer to supply code impulses of direct current to the rails of said section at a rate determined by the rate at which said relay is operated. 65
7. In combination, a section of railway track, a track transformer having a secondary winding connected across the rails of said section, a source of direct current having one terminal connected with one terminal of a primary winding of said transformer, a polar relay having a normal winding and a reverse winding, a first circuit means including said normal winding and a reverse polar contact of said relay to connect the other terminal of said current source with the other terminal of said primary winding, and a second circuit means including said reverse winding and a normal polar contact of said relay to connect said other terminal of said source with said other terminal of said primary winding whereby said relay is operated at a predetermined rate and effective code impulses of a rate equal to twice 70 said predetermined rate are supplied to the rails of said section. 75
8. In combination, a section of railway track, a track transformer having a secondary winding connected across the rails of said section, a source of direct current having one terminal connected with one terminal of a primary winding of said transformer, a polar relay having a normal winding and a reverse winding, and circuit means to connect the other terminal of said current source with the other terminal of said primary winding either over said normal winding and a reverse polar contact of the relay or over said reverse winding and a normal polar contact of the relay, and said circuit means proportioned to cause said relay to be operated at a predetermined rate so that effective code impulses of direct current of a rate equal to twice said predetermined rate are supplied to the rails of said section. 80
9. In combination, a section of railway track, a first and a second track transformer having secondary windings connected in series across the rails of said section, a source of direct current, a first and a second relay arranged with said second relay controlled over a front contact of said first relay and said first relay controlled over a back contact of said second relay to effect a cyclic operation of the relays which cycle is subdivided into four substantially equal intervals, means including a front and a back contact of said first relay in multiple to connect said current source with the primary winding of said first transformer to supply an effective impulse of current to the rails of said section during the first and the third interval of each said cycle, and means including a front and a back contact of said second relay in multiple to connect said current source with the primary winding of said second transformer to supply an effective impulse of current to the rails of said section during the second and the fourth intervals of each 85 said cycle. 90
10. In combination, a section of railway track, a first and a second transformer the secondary windings of which are connected in series across the rails of said section, a source of direct cur- 95

rent, coding means having a predetermined operation cycle which is subdivided into four substantially equal intervals, and circuit means including a first and a second contact of said coding means in multiple to connect said current source with the primary winding of said first transformer and including a third and a fourth contact of said coding means in multiple to connect said current source with the primary wind-

ing of said second transformer, and said first and second contacts opened during the first and third intervals respectively of each cycle and said third and fourth contacts opened during the second and fourth intervals respectively of each cycle to supply to the rails of said section four effective impulses of current each cycle of said coding means. 5

ANDREW J. SORENSEN.
